UNITED STATES PATENT OFFICE.

ARTHUR A. KARCHER, OF CHICAGO, ILLINOIS, ASSIGNOR, BY MESNE ASSIGNMENTS, TO UPTON MACHINE COMPANY, OF ST. JOSEPH, MICHIGAN, A CORPORATION OF MICHIGAN.

POP-GUN.

1,262,956.

Specification of Letters Patent. Patented Apr. 16, 1918.

Application filed July 31, 1913, Serial No. 782,165. Renewed July 3, 1916. Serial No. 107,484.

To all whom it may concern:

Be it known that I, ARTHUR A. KARCHER, a citizen of the United States of America, and resident of Chicago, Cook county, Illinois, have invented a certain new and useful improvement in Pop-Guns, of which the following is a specification.

My invention relates to air guns in general, but more particularly to guns of this kind in which a trigger mechanism is employed for releasing a plunger operated by a spring, and especially those adapted for use as pop guns.

The object of my invention is to provide a novel and simple form of air or pop gun involving certain details of construction tending to reduce the cost of manufacture and insure high efficiency thereof.

To these and other useful ends my invention consists in matters hereinafter set forth and claimed.

In the accompanying drawings

Figure 1, is a side elevation of a pop gun embodying the principles of my invention.

Fig. 2, is a similar view with the barrel portion of the gun shown in longitudinal section.

Fig. 3, is an enlarged perspective of the rear end of the plunger rod.

Fig. 4, is a view similar to Fig. 2, but showing the plunger drawn back.

Fig. 5, is an enlarged cross section on line 5—5 in Fig. 2.

Fig. 6, is an enlarged cross section on line 6—6 in Fig. 2.

Fig. 7, is a cross section on line 7—7 in Fig. 2.

Fig. 8, is a detail horizontal section on line 8—8 in Fig. 2.

Fig. 9, is a longitudinal section through the barrel of the gun.

As thus illustrated, my invention comprises a gun stock A to which the rear end of the barrel B is secured by screws or nails b inserted through the ears of cheeks b¹ formed at the rear end of said barrel. The said barrel is made from a sheet metal blank folded to form a round barrel, with a seam on the under side thereof. The seam is

formed by folding the edges b² of the seam backward and outward, and by then applying thereto a strip of metal C having the longitudinal edges c thereof folded over and inserted between the barrel and the

edges b² in the manner shown in Fig. 5. 55 The interlocking seam thus formed is compressed between internal and external pressure to flatten and reduce it to an air tight joint. The muzzle of the barrel is turned in and extended backward to engage and hold the ring or abutment D in place. At 60 its rear end the barrel is open on the underside thereof, for a portion of the length thereof, the sheet metal being bent downwardly to form the cheeks b² and the slot 65 b³. This formation also serves to provide a pair of ears b⁴ having inwardly projecting indentations b⁵ therein. The spring controlled trigger E having a notch e and a pivot e¹ is mounted in the said slot between 70 the ears b² and b⁴, and a lever F is mounted by a pivot f between the ears b¹. This lever has a handle f¹, and an engaging portion f² that travels in the said slot. The 75 said lever also has a pair of indentations f³ for engaging the inner-sides of the indentations b⁵, and at the time the curved points f⁴ of the lever forms a guard for the trigger, as shown in Figs. 1 and 2. The shoulders b⁶ serve to limit the insertion of the stock 80 between the ears b¹ adjacent thereto.

The plunger G fits the bore of the barrel and has a rod g formed at its rear end with a raised portion g¹ that slides against the top wall of the barrel. The down-turned 85 rear end portion g² of the plunger rod has a reduced portion g³ that slides in the slot b³ of the barrel. The portion g³ provides shoulders g⁴ that slide on the barrel at each side of the slot to support the rear end of 90 the rod. The spring H is interposed between the plunger and the cross pin h in the barrel, and serves to propel the plunger forward when the rod portion b³ is released from the notch e by pulling the trigger E. 95 The ring or abutment D limits the outward movement of the plunger and the cork I, inserted in the muzzle, is forced out by the compression of air.

The upturned end of the lever F slides 100 downward on the front side of the down-turned end portion g² of the plunger rod, when the rear end of said lever is swung downward and forward to retract the plunger. The portion g¹ and the lower end 105 of the portion g² coöperate to prevent the rear end of the plunger rod from moving up and down, and the portion g³, which

slides in the slot in the lower side of the barrel, prevents lateral movement of the rear end of said rod. As shown and described, the abutment *h* for the rear end of the spring *H* is stationary, so that said spring is compressed when the plunger is retracted, but any suitable arrangement can be employed for causing the compression of the spring at any suitable time during the general operation of moving the lever *F* forward to retract the plunger and then backward to its normal position against the under side of the gun-stock. In other words, the handle portion of the said lever *F* is first moved downward and forward, and then pulled backward against the gun-stock, when it is desired to place the entire mechanism of the gun in condition for operation by pulling the trigger. As stated, any suitable arrangement can be employed for causing the operation of the spring *H* during this manipulation of the hand lever, but for the purpose of simplicity and low cost of manufacture the abutment for the rear end of the spring may be merely a stationary pin *h*, as previously described.

The foregoing construction is simple and comparatively inexpensive, and tends to reduce the cost of manufacture, without impairing the general efficiency and serviceability of the gun. In fact the gun thus constructed has surprising power for a pop gun of this general class.

I do not limit myself to the exact construction shown and described.

What I claim as my invention is:

1. In an air gun, a barrel with a slot in the lower side thereof, a plunger in the barrel, a plunger rod having a downturned rear end provided with a reduced portion forming shoulders which rest on the barrel, and which reduced portion slides in said slot, said rod also having a raised portion that slides against the upper wall of the barrel, a lever for engaging said downturned end to draw the plunger back, and a trigger for engaging said reduced portion.

2. In an air gun, a barrel therefor formed by a sheet metal blank folded to provide a barrel with a seam on the under side thereof, the edges of said seam being turned outward, a retaining strip folded to engage between the barrel and said folded edges thereof, the lock seam thus formed being compressed to form a tight joint, a portion of said seam being omitted to form a slot, a plunger, a lever in said slot for drawing back said plunger, a trigger in said slot for catching and releasing the plunger, the muzzle of said barrel being turned inward and backward, a ring seated against the inturned edge of the said muzzle, a spring for controlling said plunger, a cross pin for engaging the rear end of the spring, and a cork fitting the muzzle of the gun.

3. In an air gun, a barrel with a slot in the lower side thereof, a plunger in the barrel, a plunger rod having a downturned rear end provided with a reduced portion forming shoulders which rest on the barrel, and which reduced portion slides in said slot, said rod also having a raised portion that slides against the upper wall of the barrel, a lever for engaging said downturned end to draw the plunger back, a trigger for engaging said reduced portion, the muzzle of said barrel being turned inward and backward, a ring seated against the in-turned edge of said muzzle, a spring for controlling said plunger, a cross pin for engaging the rear end of the spring, and a cork fitting the muzzle of the gun.

4. In an air gun, a gun stock, a barrel formed by a sheet metal blank folded to provide attaching ears that embrace said stock, a plunger fitting the bore of said barrel, a lever pivoted on the barrel for drawing said plunger back, a trigger for catching and releasing said plunger, also pivoted on the barrel, means for fixing the said ears to said stock, the muzzle of said barrel being turned inward and backward, a ring seated against the in-turned edge of the said muzzle, a spring for controlling said plunger, a cross pin for engaging the rear end of the spring, and a cork fitting the muzzle of the gun.

5. In an air gun, a barrel therefor formed by a sheet metal blank folded to provide a barrel with a seam on the under side thereof, the edges of said seam being turned outward, a retaining strip folded to engage between the barrel and said folded edges thereof, the lock seam thus formed being compressed to form a tight joint, a portion of said seam being omitted to form a slot, a plunger, a lever in said slot for drawing back said plunger, a trigger in said slot for catching and releasing the plunger, said lever having a portion that serves as a guard for said trigger, a handle portion that pulls back against the under side of the stock, and indentations on the sides thereof that engage the inner sides of indentations formed in depending ears on the barrel.

6. In an air gun, a barrel with a slot in the lower side thereof, a plunger in the barrel, a plunger rod having a downturned rear end provided with a reduced portion forming shoulders which rest on the barrel, and which reduced portion slides in said slot, said rod also having a raised portion that slides against the upper wall of the barrel, a lever for engaging said reduced portion, said lever having a portion that serves as a guard for said trigger, a handle portion that pulls back against the under side of the stock, and indentations on the sides thereof that engage the inner sides of indentations formed in depending ears on the barrel.

7. In an air gun, a barrel, a plunger in

- 5 said barrel, a spring for actuating said plunger, a trigger, said plunger having a rod bent upward to engage the top wall of the barrel and bent downward at its rear 55 end to slide on the lower side of the barrel, so that the rear portion of said rod is held by the barrel against up and down movement, a guide for the rear end of said rod, a lever pivoted below the barrel to swing 60 forward for drawing said plunger backward, an abutment for the rear end of said spring, and means to limit the forward movement of said plunger, said lever having its forward end up-turned to engage 65 and pull the down-turned rear portion of said rod into engagement with said trigger when the rear end of the lever is 70 swung forward.
8. In an air gun, a barrel, a plunger in 75 20 said barrel, a spring for actuating said plunger, a trigger, said plunger having a rod bent upward to engage the top wall of the barrel and bent downward at its rear end to slide on the lower side of the barrel, so that the rear portion of said rod is held 80 by the barrel against up and down movement, a lever pivoted below the barrel to swing forward for drawing said plunger backward, an abutment for the rear end of said spring, and means to limit the forward movement of said plunger, said lever having its forward end up-turned to engage and pull the down-turned rear portion of 85 said rod into engagement with said trigger when the rear end of the lever is swung forward, said abutment being stationary in front of said upward bent portion of the rod, so that said spring is compressed when the plunger is retracted by said lever.
11. In an air gun, a barrel, a plunger in 90 25 said barrel, a spring for actuating said plunger, a trigger, said plunger having a rod bent upward to engage the top wall of the barrel and bent downward at its rear end to slide on the lower side of the barrel, so that the rear portion of said rod is held 95 by the barrel against up and down movement, a lever pivoted below the barrel to swing forward for drawing said plunger backward, an abutment for the rear end of said spring, and means to limit the forward movement of said plunger, said lever having its forward end up-turned to engage and pull the down-turned rear portion of 100 said rod into engagement with said trigger when the rear end of the lever is swung forward, said barrel having a slot in the lower side thereof, and the rear down-turned end of said rod being shaped to slide in said slot.
- Signed by me at Chicago, Illinois, this 23d day of July, 1913.
